United States Patent Office

Des. 187,895
Patented May 10, 1960

187,895

ROTARY WING AIRCRAFT

Leon L. Douglas, Wynnewood, Pa., assignor to Vertol
Aircraft Corporation, Morton, Pa., a corporation of
Pennsylvania

Application February 2, 1959, Serial No. 54,426

Term of patent 14 years

(Cl. D71—1)

Des. 187,895

PAGE 2

FIG. 3.

FIG. 4.

FIG. 5.

FIG. 6.

Figure 1 is a top plan view of a rotary wing aircraft showing my new design with one stabilizer wing broken away for convenience of illustration only.

Figure 2 is a side elevational view.

Figure 3 is a front elevational view.

Figure 4 is a rear elevational view.

Figure 5 is a front perspective view.

Figure 6 is a rear perspective view, with the rear loading ramp down.

The conventional rotor blades are shown broken away at various points in their lengths in the several views for convenience of illustration only.

I claim:

The ornamental design for a rotary wing aircraft, substantially as shown and described.
